UNITED STATES PATENT OFFICE.

FELIX Q. RAST, OF NEW YORK, N. Y., ASSIGNOR, BY DIRECT AND MESNE ASSIGNMENTS,
TO PUBLIC SUPPLY COMPANY, OF NEW YORK, N. Y., A CORPORATION OF NEW YORK.

VENDING-MACHINE.

1,150,062.

Specification of Letters Patent. Patented Aug. 17, 1915.

Application filed October 1, 1914. Serial No. 864,371.

To all whom it may concern:

Be it known that I, FELIX Q. RAST, a citizen of the United States, and resident of New York city, borough of Manhattan, in 5 the county of New York and State of New York, have invented certain new and useful Improvements in Vending - Machines, of which the following is a specification.

My invention relates to improvements in 10 coin-controlled vending machines, and has for an object to cause the delivery of articles upon the insertion of a proper coin and to prevent the delivery of such articles upon the insertion of spurious tokens.

15 Other objects are to permit the ready removal and replacement of the receptacle for the vendible articles; to prevent the entrance of dust and germs into the machine and prevent unauthorized extraction of the 20 articles, and to provide a sanitary receiver for the vended articles.

My invention further comprises novel details of improvement and combinations of parts that will be more fully hereinafter set 25 forth and then pointed out in the claims.

Reference is to be had to the accompanying drawings forming part hereof, wherein,

Figure 1 is a partial sectional view of a vending machine embodying my invention; 30 Fig. 2 is an enlarged view, looking from the right in Fig. 1, showing part of the casing in section; Fig. 3 is a detail sectional view on the line 3, 3, in Fig. 4; Fig. 4 is a detail sectional view substantially on the line 4, 4, 35 in Fig. 3; Fig. 5 is a transverse section substantially on the line 5, 5, in Fig. 1; Fig. 6 is a fragmentary detail illustrating the discharge of a perforated token from the coin 40 receiver; Fig. 7 is a detail section on the line 7, 7, in Fig. 4, and Fig. 8 is a detail of the receiver 46.

Similar numerals of reference indicate corresponding parts in the several views.

I have illustrated my improvements as 45 adapted to deliver balls of chewing gum, candy or the like, indicated at 1, although it will be understood that the machine may be adapted to deliver goods of different form and character. To this end I have 50 shown a receptacle in the form of a glass globe 2 adapted to contain the articles to be vended, and having an opening at its lower end for the discharge of said articles, which globe is shown connected with and resting

on a plate or the like 3 that is housed within 55 a recess in a casing or frame 4. The receptacle 2 is shown bearing against a pliable gasket *a*, that is located in a recess in casing 4, whereby to exclude dust and germs from the receptacle and casing. To removably 60 connect receptacle 2 to plate 3 I have shown said receptacle provided with a bead 2^a at its open end, and a wire 5 encircling said globe adjacent to said bead and having one portion bent at 5^a and passing through an 65 opening 3^a (Fig. 5) in plate 3, the free ends of said wire being suitably bent at 5^b to pass through a slot 3^b in plate 3, said bent ends of said wire bearing under the plate. The receptacle is thus removably retained, 70 since by pressing the ends of said wire together they may be released from the slot 3^b to permit removal of the receptacle. Other means, however, may be provided for retaining the receptacle in place. The plate 75 3 is shown provided with a centrally disposed passage or opening 3^c, the surfaces of which opening are suitably downwardly shaped to cause articles 1 to pass through said opening 3^c. The plate 3 rests upon and 80 is secured to a frame or casting 6 that is secured within casing 4 and carries the article-delivering and coin-controlling devices. Frame 6 is shown provided with supporting means 6^a, which may be in the form of lugs 85 or a flange, resting upon a ledge or flange 4^a within casing 4. One of the lugs 6^a is shown provided with an upward projection 6^b (Fig. 3) entering a slot 3^d in plate 3, whereby the latter is centered and retained 90 in proper position upon frame 6. The latter is shown provided with a depending arm or rod 6^c, alongside of which depends an arm 3^e from plate 3, which arms are shown provided with registering apertures receiving a locking pin 7, whereby the parts 3 and 6 are 95 detachably secured together. Said parts are secured within casing 4 by means of a plate 8 that bears against a shoulder 4^b within casing 4 and has an opening through which 100 the arms 3^e and 6^c pass (Fig. 1), a pin 9 being passed through a hole in arm 6 close against the under side of plate 8, as shown in Figs. 1 and 2. To remove receptacle 2 for the insertion of articles 1 therein, the pin 7 is withdrawn, releasing arm 3^e from arm 6^c, whereupon the parts 2 and 3 may 105 be lifted out of casing 4, and may be readily

replaced and secured therein. To remove frame 6, with the devices it carries, the pin 9 may be removed from arm 6^c whereby plate 8 is released and frame 6 may be lifted 5 upwardly out of casing 4. Plate 8 fits snugly against shoulder 4^b to exclude dust, etc. from the casing and articles. Beneath plate 8 is a chamber 10 to receive coins, said chamber being provided above a plate 11 10 shown bearing up against a shoulder or flange 4^c within casing 4. Plate 11 is shown detachably locked to arm 6 by means of a suitable lock 12, whose bolt 12^a is adapted to engage a projection 13 at the lower end of 15 arm 6^c (see Figs. 1 and 2). Said projection is shown in the form of a screw entering a threaded opening in the lower end of arm 6^c, whereby said projection may be adjusted with respect to bolt 12^a for properly locking 20 plate 11 within casing 4. The devices described afford a simple and convenient means for retaining the receptacle 2, plate 3 and frame 6 within and upon casing 4, and providing a secure chamber for coins, 25 but such particular form of devices may be varied insofar as they relate to the below devices for delivering articles.

Within a suitable chamber or space 14 within casing 4 is rotatively mounted an 30 article discharger 15, shown comprising a central hub-like portion provided with outwardly or radially disposed fingers or arms 15^a, having spaces therebetween adapted to receive the articles 1 to be delivered. Said 35 discharger 15 is shown mounted upon a shaft or pin 16 carried by frame 6. The chamber or space 14 is but slightly wider than the discharger 15, so that the articles will be guided through said chamber by the 40 fingers or arms 15^a, and the distance between the wall 6^c and the ends of said fingers or arms (Fig. 3) is such that, as said discharger is rotated, the articles 1 will be properly delivered, preferably in a suitable chute 17 45 that is shown cast integrally with frame 6, and having its lower open end close above an opening 8^a in plate 8 for the discharge of articles therethrough. The discharger 15 is to be rotated step by step by interposed 50 coins, and is retained in proper position after each step by means of a suitable spring 18 that is shown secured to frame 6 and bent so as to pass between two fingers 15^a, the 55 lower portion of the spring bearing upon one finger or arm 15^a and the upper free portion of the spring bearing under an upper finger or arm, whereby said discharger may be rotated in the direction of the arrow in Fig. 3, but its reverse rotation is prevented by said spring. Below discharger 15 60 is an oscillatory or rocking coin-receiver 19, that is secured upon a shaft 20 journaled on frame 6. Coin receiver 19 is provided with an upwardly directed recess 19^a shown in 65 the form of a jaw adapted to receive coins

21, which when in proper position in the jaw of said receiver bear at an edge against a wall or abutment 17^a (Fig. 4). The coins are placed in the machine through a slot 22, shown formed in an extended portion 23 70 of frame 6, beneath which is a suitable guideway or chute 24 leading downwardly and terminating over and in alignment with the jaw of receiver 19, whereby the coins are guided into the latter. Said chute is 75 shown cut away to some extent on one side and provided with openings 25, 26 for the escape of spurious articles that may be inserted through the coin slot. To prevent light-weight tokens from reaching the coin 80 receiver 19, I provide a balanced or weighted finger 27, that is pivoted upon the chute at 28, projects through a suitable opening 29 in the bottom of the coin chute, and normally lies in the path of coins traveling 85 down the chute, the weighted portion 27^a in conjunction with a stop 27^b (Fig. 4) serving to retain the finger 27 in such position. The arrangement is such that when a proper coin passes through the coin chute it will 90 ride upon and tilt finger 27 to permit the passage of the coin to the coin receiver, but if a coin or token of too light weight to swing finger 27 downwardly is passed into the coin slot, it will ride up on said finger 95 and its upper portion will encounter a laterally inclined projection 30 (Figs. 2, 4 and 7) that extends from the upper portion of the coin chute, so that thereby such light-weight coin or token will be caused to pass 100 sidewise out of the coin chute and drop below. The position of the coin receiver 19 is such that when a proper coin enters the same, its upper portion will be opposed to one of the fingers or arms 15^a of the discharger 15 (Fig. 3), whereby when said receiver is rocked with the coin the latter will engage such finger and thereby the discharger will be rotated a step. The arrangement of spring 18, as shown, is such 110 as to accelerate the final motion of the distributor as a finger 15^a passes under said spring, which is effected by reason of the curving upper portion 18^a of said spring bearing elastically against the under portion 115 of an advancing finger 15^a. The jaw 19^a of coin receiver 19 is shown inclined downwardly (to the left in Fig. 4) whereby when the coin is caused to pass adjacent to and beyond the edge of abutment 17^a (Fig. 3) 120 said coin will be discharged from the receiver to fall into a chute 31 that is carried upon plate 8, a slot being provided in said plate beneath said chute for the discharge of coins into chamber 10. Beneath the slot under chute 31 I preferably provide a downwardly directed ledge or the like 31^a upon which the coins roll to direct them to a distance from said slot within chamber 10 to prevent the coins from piling up directly 125 130

under said slot. At 32 (Fig. 3) is a stop or abutment carried by frame 6 and located in such position, relatively to the delivery of the coin, that the upper portion of the coin will engage said stop to aid in causing the dislodgment of the coin from receiver 19.

Any suitable means may be provided for rocking the coin receiver 19. To this end I have shown a push rod 33 that is shown guided in plate 23 and in a bearing 34 on frame 6, a spring 35 coiled upon said rod and connected at its upper end therewith and pressing against the bearing 34 serving normally to keep said rod raised. Rod 33 is shown provided at its lower end with a head 33^a provided with a suitable slot 33^b (Fig. 4) receiving an arm 36 that is secured to shaft 20. The arrangement is such that when rod 33 is in the normal position the arm 36 will be raised, as in Fig. 2, to retain the coin receiver 19 in register with the coin chute, and whereby when rod 33 is pushed downwardly, and arm 36 is depressed, said receiver, with the coin therein, will be rocked so that the coin will engage one of the fingers 15^a to rotate the distributor 15 one step, the coin 20 then assuming a proper position within the jaw of said receiver for causing the coin to operate the distributor. The slot 33^b permits proper play of arm 36 along head 33^a as rod 33 reciprocates. To prevent spurious tokens having holes therein, such as washers, from operating the distributor 15, and to cause such tokens to be discharged from the coin receiver, I provide a pin 37 upon a rocking arm 38 that is pivoted upon frame 6 at 39, the depending portion 38^a of said arm having an inclined lower edge 38^b (Fig. 1), in position to be engaged by arm 40, which may be an extension of arm 36 (Fig. 2). The normal position of pin 37 is substantially at the center of a washer or apertured token, located in receiver 19, and the arrangement is such that when such washer or token enters the coin receiver 19, said washer or token will tilt toward pin 37, so that the latter will enter the hole in the washer or token (Fig. 6) and then when rod 33 is pushed inwardly and arm 40 is caused to rise against the inclined edge 38^b of arm 38 the pin 37 will be raised and will lift the washer or token out of receiver 19. To aid further in dislodging the washer or apertured token, I provide a finger 41 that is operated with coin receiver 19, and which moves toward the washer, in a path to one side of the pin 37 and relatively close to the latter, in position to engage the washer that is lifted by said pin to dislodge the washer from said pin, and said washers or tokens will fall upon plate 8. The finger 41 may be formed on or secured to coin receiver 19.

Beneath the opening 8^a I provide a suitable chute 42 for the articles 1 (Fig. 2), which chute is shown carried by plate 11

and communicates with a discharge opening 4^a in the base of casing 4. Chute 42 is secured dust-tight upon plate 11 and said chute at its upper end fits snugly against plate 8, and, furthermore, as plate 11 fits 70 snugly against shoulder 4^c, the entrance of dust from below into the mechanism and receptacle 2 is resisted, aided by the tight closure of door 43 against plate 8. Beneath opening 8^a is a door 43, shown hinged upon plate 8, at 44 (Fig. 2), and normally held up against plate 8, as an abutment at opening 8^a, by a suitable spring 45. This arrangement is such that when articles 1 pass down chute 17 they cause the opening of door 43 in their 80 passage to chute 42, which door swings into said chute, and when said door is normally closed it prevents the entrance of dust, germs, etc., into the machine. The door 43 also serves to prevent the unauthorized insertion of wires or the like into the machine in an effort to extract articles.

At 46 is a receiver for the articles 1 that are delivered. Said receiver is shown in the form of a wire bent between its ends to provide a pair of substantially parallel arms, and bent at its outer end portion, at 46^a, in substantially hook-like form, whereby the articles 1 may rest in said receiver in convenient position for removal by the fingers. 95 Hence, as the ordinary circulation of air may take place through said receiver, and but a limited surface is exposed to the articles, the latter are kept free from accumulating dust and the like. The receiver 46 is 100 carried by plate 11, and may be secured thereto or to chute 42 in any suitable manner, as by solder.

Changes may be made in the details of construction and arrangements of parts 105 shown and described, as the same may be varied, within the scope of the appended claims, without departing from the spirit of the invention.

Having now described my invention what 110 I claim is:—

1. In a vending machine a movable coin receiver, a pin separate from the receiver adapted to enter an apertured token while in the receiver, means movably supporting said pin to have motion relatively to the receiver to lift such token from the receiver, and means to operate the receiver and the pin. 115

2. In a vending machine a movable coin receiver, a pin separate from the receiver adapted to enter an apertured token while in the receiver, means movably supporting said pin to have motion relatively to the receiver to lift such token from the receiver, 120 means to operate the receiver and the pin, and a finger movable with the receiver to dislodge tokens from said pin. 125

3. In a vending machine a coin receiver, a pin adjacent to the receiver to enter an aper-

tured token therein, a pivotal arm carrying said pin, and means to operate said receiver and arm coincidently.

4. In a vending machine a movable coin receiver, a pin adjacent to the receiver to enter an apertured token therein, a pivotal arm carrying said pin, means to operate said receiver and arm coincidently, and a finger movable with said receiver to dislodge tokens from said pin.

5. In a vending machine a coin receiver having a recess for coins, means to rotatively support said receiver, an arm pivotally supported adjacent to said receiver, a pin carried by said arm above the receiver to enter apertured tokens therein, an arm connected with said receiver to actuate the first named arm, and means to rock said receiver.

6. In a vending machine a coin receiver having a recess for coins, means to rotatively support said receiver, an arm pivotally supported adjacent to said receiver, a pin carried by said arm above the receiver to enter apertured tokens therein, an arm connected with said receiver to actuate the first named arm, a push rod, and means operatively connecting the push rod with said receiver for rocking the latter.

7. In a vending machine a coin receiver

having a recess for coins, means to rotatively support said receiver, an arm pivotally supported adjacent to said receiver, a pin carried by said arm above the receiver to enter apertured tokens therein, an arm connected with said receiver to actuate the first named arm, a push rod having a head provided with a slot, and an arm connected with said receiver and entering said slot, whereby the receiver may be rocked upon operation of said rod.

8. In a vending machine a movable coin receiver, a pin separate from the receiver adapted to enter an apertured token while in the receiver, means movably supporting said pin to have motion relatively to the receiver to lift such token from the receiver, means to operate the receiver and pin, and an abutment spaced from said receiver in position to engage a coin to dislodge it from the receiver when the latter is rocked.

Signed at New York city, in the county of New York, and State of New York, this 25th day of September A. D. 1914.
